[57] CLAIM

The ornamental design for rotatable sign, as shown and described.

DESCRIPTION

FIG. 1 is a side elevational view of a rotatable sign showing my new design thereof, with the opposite sides being a mirror image and with the support pole broken away to indicate indeterminate length;

FIG. 2 is a front elevational view thereof, with the rear panels being a mirror image;

FIG. 3 is a top perspective view thereof.

FIG. 1

FIG. 2

FIG. 3
